UNITED STATES PATENT OFFICE.

GASTON STROBINO, OF PATERSON, NEW JERSEY.

SOUND REPRODUCER.

Application filed February 17, 1926. Serial No. 88,835.

The object of this invention is to provide a resonator to be put in a state of resonance, and to be used like the so-called "loud-speaker" in connection with radio apparatus, by vibrations imparted thereto as the result of electrical impulses imparted to an electro-magnetic actuator. In the device illustrated herein by way of example the resonating body includes two concavo-convex parts, as of wood, bearing against each other at their peripheries, with outlet means for the escape of sound emanating within the body thus formed.

In the drawing,
 15 Fig. 1 is a plan of the device;
 Fig. 2 is a side elevation, partly in section; and
 Fig. 3 is a central vertical section of a fragment of the device, on a larger scale.
 20 In said drawing, 1—1 designates the upper and lower concavo-convex parts, as of wood, bearing against each other at their peripheries, being there held together by the screw-bolts 2. The upper one has a
 25 sound outlet 3 and the lower one preferably has supporting legs 4.

5 is a member, in the present case formed horse-shoe shaped with its ends bent off in opposite directions and threaded and formed
 30 or provided with shoulders 5^a against which bear the washers 5^b; this is of metal and preferably a permanent magnet. It is housed within the resonator, which thus forms a casing and has its threaded ends
 35 passed through central holes in the parts 1—1 and fitted with nuts 6—6, which when screwed up tight establish all the parts 1—1, 5 and 6—6 in fast relation to each other. The position of member 5, it will be noted,
 40 is such that vibration of either arm thereof will be in the same direction as vibration of the resonator-forming parts or walls 1—1, or vertically in the present example.

On soft-iron prolongations 7—7 of the arms of said member, which are bent toward each other and have their free ends opposed, are the coils 8—8 electrically connected together as at 8^a and arranged in a suitable exciting circuit so that in the periods of excitation of the electro-magnets formed by the coils and their cores 7—7 magnetic attraction will overcome the resistance of said member (which is elastic) to undergo change in its form and intermittently tension it, drawing the arms toward each other, they of course receding as soon as the at-

traction ceases. The coils are assumed to be in a circuit over which a current made undulatory by the action of sound waves is transmitted; this circuit is shown as comprising the conductors 10, the clips 10^a to which they are connected and the leads 10^b connecting the clips with the electro-magnets.

The prolongations 7—7 (which form the cores of the electro-magnets and each of which in the present case is the armature of the opposite magnet) are arranged as close as possible together without touching in the vibrating of the member 5, and means is provided whereby the member may be put in a desirable state of tension and the cores brought together to the proper spacing. To this end, 11 is a plate-spring, preferably of metal, which has one end bearing outwardly against the washer 5^b on one arm of member 5 and its other end bent off to form a foot 11^a to rest on the relatively opposite part or wall 1 of the resonator, and 12 is a screw penetrating the said resonator part 80 and this spring and having its head bearing on the spring and a thumb-nut 13 to bear against said part.

In my device the actuator afforded by either electro-magnet has a fixed connection with a resonator, as for example the lower electro-magnet 8 with the lower resonating part 1, and vibrations set up in the actuator by variations in the electric current produce vibrations of the resonator, the construction being preferably such as shown that such resonator has a projection afforded by the relatively remote arm of member 5, vibratory independently of the resonator, and the actuator and its armature are arranged 90 so that one is on said projection and the other on some portion of the structure including the resonator and projection with respect to which the projection is independently vibratory, so that sound is the result 95 not merely of molecular disturbance in the actuator but of the magnetic force being utilized to intermittently tension this vibratory structure. In this and other respects the present device embodies the principles 100 of the invention set forth in my application Serial No. 74,276.

But in the present case I have not merely interposed an elastic element as 5 between two resonators so that it becomes as to each such resonator an independently vibratory projection therefrom: I have given these 110

- resonators 1—1 a support on each other and formed them so that one at least presents a concave side or hollow to the other. I have further provided means, 11—12—13, where-
 5 by the structure formed by the two resonators is tensioned, and whereby also the member 5 is also tensioned and the distance between the poles of the electro-magnets calibrated.
- 10 Having thus fully described my invention what I claim and desire to secure by Letters Patent is:
1. A resonating structure including, with two opposite portions supported one on the other, one being resonant and one having a hollow presented to the other, and an elastic vibratory element forming a projection from the resonant portion vibratory independently thereof, means holding said portions and elements in a state of tension, and means to vibrate said element and thereby the resonant portion.
  2. A resonating structure including, with two opposite portions supported one on the other, one being resonant and one having a hollow presented to the other, and an elastic vibratory element forming a projection from the resonant portion vibratory independently thereof, elastic means holding said portions and element in a state of tension, and means to vibrate said element and thereby the resonant portion.
  3. A resonating structure including, with two opposite portions supported one on the other, one being resonant and one having a hollow presented to the other, and an elastic vibratory element forming a projection from the resonant portion vibratory independently thereof, adjustable means to tension said portions and element, and means to vibrate said element and thereby the resonant portion.
  4. A resonating structure including, with two opposite portions supported one on the other, one being resonant and one having a hollow presented to the other, and an elastic vibratory element forming a projection from the resonant portion vibratory independently thereof, adjustable means to tension said portions and element, and means to vibrate said element and thereby the resonant portion, the former means being elastic.
  5. A resonating structure including, with two opposite portions supported one on the other, one being resonant and one having a hollow presented to the other, and a bent elastic vibratory element forming a projection from the resonant portion vibratory independently thereof, means holding said portions and element in a state of tension, and an electro-magnetic actuator and its armature arranged on said element on opposite sides of its bend and held by the latter in operative relation to each other as said element is thus tensioned.
  6. The combination of a resonating structure including a resonant hollow casing and a vibratory element contained in the space of said casing and forming a projection therefrom vibratory independently thereof, means to vibrate said element and thereby the casing and means holding the casing tensioned. 70
  7. The combination of a resonating structure including a resonant hollow casing and a vibratory element contained in the space of said casing and forming a projection therefrom vibratory independently thereof, means to vibrate said element and thereby the casing, and elastic means holding the casing tensioned. 75
  8. The combination of a resonating structure including a resonant hollow casing and a vibratory element contained in the space of said casing and forming a projection therefrom vibratory independently thereof, means to vibrate said element and thereby the casing, and adjustable means to tension said casing. 85
  9. The combination of a resonating structure including a resonant hollow casing and a vibratory element contained in the space of said casing and forming a projection therefrom vibratory independently thereof, means to vibrate said element and thereby the casing, and adjustable means to tension said casing, the latter means being elastic. 90
  10. The combination of a resonating structure including a resonant hollow casing and an elastic vibratory element contained in the space of said casing and forming a projection therefrom vibratory independently thereof, means to vibrate said element and thereby the casing, and means holding said casing and element tensioned. 100
  11. The combination of a resonating structure including a resonant hollow casing and an elastic vibratory element contained in the space of said casing and forming a projection therefrom vibratory independently thereof, means to vibrate said element and thereby the casing, and elastic means holding said casing and element tensioned. 105
  12. The combination of a resonating structure including a resonant hollow casing and an elastic vibratory element contained in the space of said casing and forming a projection therefrom vibratory independently thereof, means to vibrate said element and thereby the casing, and adjustable means to tension the casing and said element. 115
  13. The combination of a resonating structure including a resonant hollow casing and an elastic vibratory element contained in the space of said casing and forming a projection therefrom vibratory independently thereof, means to vibrate said element and thereby the casing, and adjustable means to tension the casing and said element, the latter means being elastic. 125

14. The combination of a resonating structure including a resonant hollow casing and a bent elastic vibratory element contained in the space of said casing and having its extremities rigidly connected to spaced points of the casing, means holding the casing and said element in a state of tension and an electro-magnetic actuator and its armature arranged on said element on opposite sides of its bend and held by the latter in operative relation to each other as said element is thus tensioned. ¹⁰
- In testimony whereof I affix my signature.

GASTON STROBINO.
